METHOD OF MAKING QUOITS

Arley D. McClintock, Nescopeck, Pa.

Application June 22, 1932, Serial No. 618,748

1 Claim. (Cl. 29—156)

This invention relates to quoits, and has generally in view to provide an improved quoit and a novel method of producing the same.

Heretofore, most commercial quoits have been cast from iron or steel, as this has proved to be the most economical production method permitting their sale at what is generally considered a reasonable price. On the other hand, higher grade, higher priced quoits are, in some instances, hand forged and in other instances machine turned from steel bars.

Cast quoits, while capable of being produced economically, are not satisfactory in use. They are brittle even when cast from malleable iron and they soon become chipped, dented and slivered. Moreover, they are easily broken and frequently break in use.

Hand forged quoits are never entirely uniform either in size or weight. Moreover, their cost is relatively high, and since they are formed from bars bent to shape and welded at their ends they tend to crack and open at the weld.

Machine turned quoits, on the other hand, while satisfactory in use, are entirely too expensive to produce to be practicable from a commercial standpoint.

Accordingly, a special object of the present invention is to provide a quoit which compares favorably with cast quoits as to production cost, and which eliminates the disadvantages of cast quoits and retains the advantages of the higher priced hand forged or machine turned quoits. That is to say, while the present quoit is of comparatively low production cost, (being either a drop-forged or pressed-product) it is devoid of welds, has little or no tendency to crack or break despite the harshest usage, is not easily dented and does not chip or sliver in use.

Another special object of the invention is to provide a practical method of producing the present drop-forged or pressed quoit economically and in such manner that it possesses the advantages set forth.

With the foregoing and other objects in view, which will become more fully apparent as the nature of the invention is better understood, the same consists in a quoit having the novel structural features, and in the novel steps of the method employed in producing the same, as will be hereinafter more fully described, illustrated in the accompanying drawing and defined in the appended claim.

In the drawing, wherein like characters of reference denote corresponding parts in the different views:—

Figure 1 is an elevation of a bar or blank of metal from which the quoits are formed.

Figure 2 is an elevation illustrating the first step of the method.

Figure 3 is an elevation illustrating the second step of the method.

Figure 4 is a sectional view illustrating the third step of the method.

Figure 5 is a sectional view illustrating the fourth step of the method.

Figure 6 is a sectional view illustrating the fifth step of the method and the finished quoit; and

Figure 7 is a plan view of the finished quoit.

Referring to the drawing in detail, particularly to Figs. 6 and 7, it will be observed that the present quoit is, in general, of conventional design in that it is in the form of a metal ring 10 of greatest thickness adjacent to the central hole 11 therein and tapered outwardly to a relatively thin edge 12, but that it is a departure from standard quoit structural design in that its bottom face 13 is flat and inclined upwardly and inwardly, in that its central hole 11 is defined medially by a vertical wall 14 which is rounded outwardly at 15 its top and bottom as at 16 and 17, respectively, into gradual merger with the top and the bottom quoit faces 17 and 13, respectively, and in that its top face 17 has a pronounced convex curvature. 15

As a result of the upward and inward inclination of its bottom face 13 the present quoit has a pronounced tendency when tossed in the usual manner and upon striking the ground to enter the ground at its forward edge and therefore to remain in the position where it strikes the ground rather than to slide, even though the quoit may be disposed practically horizontally when it strikes the ground. On the other hand, due to the 20

rounding or convex curvature of the upper face 17 thereof the quoit when inverted and tossed has little or no tendency to remain in the position where it strikes the ground, but has a distinct tendency to slide or roll, which, of course, is quite 25

advantageous under certain conditions in pitching the game of quoits. Moreover, due to the wall of the hole 11 being vertical except when 30

it is rounded at its top and bottom corners to afford comfortable finger engaging surfaces and to avoid sharp corners which might be likely to chip or sliver, the greater mass of metal of the quoit is concentrated near the center thereof whereby the quoit tends to remain in flight in the same position in which it leaves the hand of the tosser, rather than to turn or roll in flight. 35

In accordance with conventional practice the 40

present quoit is notched at its edge, as at 18, for finger engagement, and is provided with suitable means for identifying it with its mate, this last named means consisting, for example, of a recess or recesses 19 suitably formed in the upper side of the quoit during manufacture thereof.

In the manufacture of quoits according to the present method a bar 20 of suitable metal, such as open hearth steel of appropriate length, width and thickness, is cut in any suitable manner, as indicated by the dotted lines 21 in Fig. 1, into short, substantially rectangular sections 22 as indicated in Fig. 2, and the corners of these sections then are removed in any suitable manner to provide quoit blanks 23 of substantially octagonal shape as illustrated in Fig. 3. Next, the blanks 23 are heated to a white heat and drop-forged or pressed to approximately final shape between a pair of dies 24 and 25 as illustrated in Fig. 4. In this connection it will be observed that the dies are parted along the line of the outer edge of the quoit and that they are formed with central projections 24', 25', respectively, which serve to shape the central portion of the quoit and partially to form the central hole 11 therein by squeezing the metal of the blank into a relatively thin web 26 extending across the partly formed hole, approximately midway between the top and the bottom faces of the quoit.

Following the drop forging or pressing operation, which leaves the web 26 remaining in the partially formed hole 11, and which usually leaves a fin or flashing indicated at 27 in Fig. 4, projecting from the outer edge of the quoit where the dies are parted, the web 26 is punched, cut or otherwise suitably removed from the hole 11 and the fin or flashing 27 is sheared off. The rough surfaces remaining where the web and the flashing are removed then are ground or otherwise trued and finished and the quoit is completed by

grinding or otherwise forming the notch 18 and the identification mark or marks 19 therein. If desired, however, the notch 18 may be partially formed during the drop forging or pressing operation to be subsequently finished by grinding, and the upper die may be provided with either a suitable projection or depression to form a raised or depressed identification mark on the quoit during drop-forging or pressing of the same.

The completed drop-forged or pressed quoit is strong and durable and is not easily cracked, broken or chipped. Moreover, it is of comparatively low production cost and due to its peculiar structural shape has the previously mentioned advantages in use.

Without further description it is thought that the features and advantages of the invention will be readily apparent to those skilled in the art, and it will of course be understood that changes in the form, proportion and minor details of construction may be resorted to, without departing from the spirit of the invention and scope of the appended claim.

I claim:—

The method of making machine forged quoits which consists of cutting a section from a bar of strip open-hearth steel stock of suitable thickness to provide a blank, roughly forming the said blank into substantially disk form, heating the blank, subjecting the heated blank to pressure between dies simultaneously to form the body of the quoit in final shape by die squeezing the metal into the body and partially forming a central hole, thus leaving a central web; removing the web from the center of the formed body; removing the excess metal from around the peripheral edge of the formed quoit body; and then grinding away any remaining portions of the web and peripheral metal.

ARLEY D. McCLINTOCK.
